Primary Examiner — Rebekah A Caruso(74) *Attorney, Agent, or Firm* — Che-Yang Chen; Law Office of Michael Chen(57) **CLAIM**

The ornamental design for a toilet brush with holder set, as shown and described.

DESCRIPTION

FIG. 1 is a perspective view of the toilet brush with holder set showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view thereof when it is being used. The broken lines shown in the drawings represent portions of the toilet brush with holder set that form no part of the claimed design.
